Application November 18, 1953, Serial No. 27,653

Term of patent 14 years

(Cl. D14—27)

Fig. 1 is a three-quarter view in perspective of an automobile embodying our new design;

Figs. 2 and 3 are side elevation and top plan fragmentary views, respectively, of the automobile of Fig. 1; and

Fig. 4 is a fragmentary longitudinal sectional view taken along the lines 4-4 of Fig. 3.

The characteristic features of our design reside in the portions shown by means of full lines in the drawings.

We claim:

The ornamental design for an automobile, as shown and described.
